United States Patent Office.

LOUIS S. ROBBINS, OF NEW YORK, N. Y.

Letters Patent No. 78,285, dated May 26, 1868.

IMPROVEMENT IN AGRICULTURAL STEAM-BOILERS.

The Schedule referred to in these Letters Patent and making part of the same.

TO ALL WHOM IT MAY CONCERN:

Be it known that I, LOUIS S. ROBBINS, of the city, county, and State of New York, have invented a new and improved Agricultural Steam-Boiler; and I do hereby declare that the following is a full, clear, and exact description thereof, which will enable others skilled in the art to make and use the same, reference being had to the accompanying drawings, forming part of this specification.

This invention relates to improvements in boilers which are used for agricultural purposes, as for steaming or boiling feed for cattle, horses, or other live stock, heating water, and generating steam for other purposes; and it consists in the construction and arrangement of the various parts hereinafter more fully described. The drawing—

Figure 1, is a vertical section of the boiler, surrounded by its casing, and showing the general arrangements of the parts connected therewith, the section being through the line *x x* of fig. 2.

Figure 2 is a vertical section of fig. 1 through the line *y y*.

Figure 3 is an outside view, and

Figure 4 is a detail view of the vacuum and safety-valve.

Similar letters of reference indicate corresponding parts.

A is the casing around the boiler, with the fire-box in its base, and a sunken ash-pit beneath the grate-bars.

B is the boiler, which is cylindrical in form, with a crowning or concave bottom, and with a hemispherical cap or cover marked C.

D is the fire-box.

E is the ash-pit.

F represents the fire-flue around the boiler.

G represents the door for the introduction of the fuel.

On the inside of the fire-box D, to protect the casing and fire-box from injury from the heat of the fire, I place corrugated plates of metal, H, as seen in the drawing, fig. 1.

These corrugated plates prevent injurious contact between the incandescent fuel and the more destructible walls and bottoms of the fire-box.

B' represents a deflecting-plate in the flue F, to prevent the products of combustion from passing directly into the chimney-pipe C'. This plate is supported by the rod D' from the bottom of the flue F.

The bottom of the boiler I is made arching or concave, for the purpose of more fully concentrating and confining the heat, as well as to increase the fire-surface, and also so that the contents of the boiler may be drawn off by a pipe attached near the bottom, and in such a position that the said pipe may be properly protected from the intense heat.

In the ordinary cauldron-kettle boiler, with its convex bottom, this cannot be accomplished with any degree of success.

J is the supply-pipe attached to the boiler, as seen in the drawing, with the inner end, which passes through the flue F, protected by a cast-iron sleeve, K, or a sleeve made of any incombustible material.

L is a branch-pipe, with a cock, through which the entire contents of the boiler may be drawn off. The supply-pipe J extends upward, and connects with a water-reservoir, m, near the top of the casing. The water in the reservoir will be more or less heated from the casing, and thereby fitted for the boiler.

n is a stop-cock to shut off the water from the boiler. This cock may be partially open, so as to supply a uniform quantity of water while steam is being generated.

O is a test-cock for determining the quantity of water in the boiler. The cap is provided with an annular flange, p, with concave channel, which fits into and on to a corresponding flange, q, on the boiler, as seen in the drawing. Lead or other suitable packing is placed between the flanges, and the two are secured tightly together by screw-bolts, as seen.

R is the pipe through which steam is discharged for steaming vegetables or boiling in separate vessels; as barrels, tanks, &c.

S is a combined vacuum and safety-valve, the tube of which passes loosely through the cap into the steam-space of the boiler.

T is a spring-valve attached to a collar on the lower end of the tube S. The valve closes the end of the tube by the pressure of the spring, except when a vacuum is produced in the boiler; in that case the pressure of the atmosphere forces it open for the admission of air. It will be noticed that the lower portion of the tube is somewhat tapering, as seen more distinctly in the detached view, fig. 4, at w.

The manner in which it operates as a safety-valve is as follows: As seen in the drawing, the flange V of the tube S rests on the cap. w w represent weights or rings on the tube, which may be more or less in number or weight. When the pressure in the boiler is sufficiently high to raise the tube and weights upon it, the tube will be lifted up through the orifice in the cap till the tapering portion, u, reaches the orifice, when steam will be discharged through the annular opening thus formed, which immediately relieves the pressure, and the tube drops back to its place. Elastic packing is placed between the flange or collar V and the cap to prevent the leakage of steam.

Having thus described my invention, what I claim as new, and desire to secure by Letters Patent, is—

1. The corrugated plates H in the fire-box, substantially as and for the purposes described.
2. I claim the protecting-sleeve K on the pipe J, substantially as described.
3. I claim the supply-pipe J, provided with the cocks n, o, and L, and connected with the water-reservoir m, substantially as described.
4. I claim the method of forming the joint between the cap G and the boiler, substantially as described.
5. I claim the combined vacuum and safety-valve, constructed and operating substantially as shown and described, for the purposes specified.

LOUIS S. ROBBINS.
